JET DRIVE FOR BOATS OR THE LIKE

John P. Myers, 407 N. Maple Drive, Beverly Hills, Calif.

Filed Jan. 30, 1961, Ser. No. 63,765

Term of patent 7 years

(Cl. D71—1)

FIGURE 1 is a top perspective view of a jet drive for boats or the like, showing my new design;

FIGURE 2 is a side elevational view thereof, the opposite side being the same in appearance;

FIGURE 3 is a rear elevational view; and

FIGURE 4 is a bottom plan view.

I claim:

The ornamental design for a jet drive for boats or the like, substantially as shown and described.
